UNITED STATES PATENT OFFICE.

JOHN HEBERLING, OF ROCHESTER, NEW YORK, ASSIGNOR, BY MESNE ASSIGNMENTS,
TO REMINGTON RAND INC., OF NEW YORK, N. Y., A CORPORATION OF DELAWARE.

COPYHOLDER.

Application filed April 2, 1927. Serial No. 180,396.

My present invention relates to copyholders and particularly to copyholders of the kind used in connection with and for transcribing upon typewriters wherein the copy holding means is disposed at the rear of the typewriter and forwardly extending bracing and operating means project at the side of the machine. Such copyholders embody either a stationary copy-plate and a relatively movable line indicator which follows down the copy or a movable copying plate associated with a fixed line indicator. In either case the relative movement of the elements is effected with a step-by-step movement through suitable actuating mechanism. The invention has for its object to provide for such copyholders a simple convenient and efficient regulating mechanism for controlling the length of the step taken by the actuating mechanism on each operation to adjust the line indication to conform with the spacing of the copy.

To these and other ends the invention resides in certain improvements and combinations of parts, all as will be hereinafter more fully described, the novel features being pointed out in the claims at the end of the specification.

In the drawings:

Figure 1 is a front elevation of the copyholder constructed in accordance with and illustrating one embodiment of my invention;

Figure 2 is an enlarged fragmentary elevation of a portion of the copyholder support showing the front view of my improved stop mechanism;

Figure 3 is a side elevation of the parts shown in Figure 2 partially in section on the lines 3—3 and 3a—3a of Figure 2;

Figure 4 is a horizontal section on the line 4—4 of Figure 2;

Figure 5 is a further enlargement in the same sectional plane of certain parts shown in Figure 4; and

Figure 6 is a detail section on the line 6—6 of Figure 2.

Similar reference numerals throughout the several views indicate the same parts.

I have illustrated my invention in the present instance and will describe it as applied to the familiar type of copyholder embodying the stationary line indicator and a movable copy-plate. Referring more par-

ticularly to Figure 1, 1 indicates the copy-plate having a paper clip or clamp 2 at the top thereof and movable vertically upon guide rods 3 on an upright supporting frame 4. The supporting frame, in the present instance, consists of a plate embossed rearwardly at 5 and having forwardly extending flanges 6 at its edges. It is secured at the bottom to a heavier reinforcing base plate 7 while the flange at the top forms a sliding bearing for a lifting rod 8 carried on the back of the copy-plate. A lifting clutch 9 carried by a reciprocatory clutch rod 10 engages the rod 8 above the frame while an independently supported holding clutch 11 engages the rod 8 below the frame. The clutch 9, as the clutch rod 10 is raised, raises the copy-plate and while it is returning to initial position the clutch 11 maintains the plate against retrograde movement so that a step-by-step upward advance of the copy-plate past a stationary line indicator 12 disposed across its face and suitably supported by the frame 4 is effected. When the clutch rod 10 is abnormally depressed or lowered it releases both clutches and the plate falls to a lowermost position. It is shown in a partially raised position in the figures. The foregoing mechanism is well known in the prior art and my present invention is concerned with it only in a general way for which reason the parts have been illustrated largely by dotted lines.

The frame and copy-plate are held erect at the rear of the typewriter by a forwardly extending side arm 13 that lies at the side of the typewriter. Pivoted to this arm at 14 is an operating lever 15 the forward end of which is in the form of a handle or finger key 16 that projects for accessibility and convenience to the operator adjacent to the key board of the typewriter. The rear end of the operating lever 15 is operatively connected through a universal joint at 17 to the outer end of a relatively angularly disposed actuating lever 18 to which the lower end of the clutch rod 10 is pivoted at 19. This actuating lever is a lever of the second order being pivoted to the main supporting frame plate 4 at 20. It will, therefore, be seen that by depressing the operating lever 15, the copy-plate 1 will be raised one step through a consequent movement of the actuating lever 18 and the clutch rod 10. The degree

of raising movement is limited by the stop mechanism of the present invention which will now be described in detail.

A side flange 6 of the supporting plate 4 is slotted at 21, 22 and 23. The end of the actuating lever 18 projects through and is guided in the slot 21. Slidable in the angle between the flange and plate is an angular carriage plate 24 having rigidly secured thereto an exteriorly and interiorly threaded stud 25 that projects through and is guided in the slot 22 of the side flange. By means of a nut 26 having a knurled head the carriage may be tightened in position and held at any desired position of adjustment. This mechanism, so far described, constitutes a rough adjustment for the stop device hereinafter referred to.

Pivoted to the angular carriage plate 24 by a shouldered rivet 27 (see Figure 6) is a stop plate 28 which is also angular having a flange 29 paralleling the corresponding portion of the carriage plate. A depending arm 30 on the stop plate terminates in a rubber or other suitable buffer 31 lying above and in the path of the actuating lever 18. The coarse adjustment of the carriage 24 above described advances or retracts the stop buffer 31 in the path of the lever, and the stop is held retracted to a maximum extent on the carriage by a spring 32 hooked on to the latter at 33 and to the stop plate at 34.

To provide a fine adjustment of the stop and more accurately control the throw of the actuating lever 18 and the consequent line indicating movement with reference to the copy, the flange 29 of the stop plate is provided with a bearing socket 35 bumped out therefrom and which engages and turns the inner end of a screw 36 extending through the stud 25 and terminating in another and preferably smaller knurled head 37 beyond the knurled head 26. This constitutes a limiting contact for the stop plate 28 in its retracting pivotal movement under the influence of the spring 32, so that by loosening the screw the stop is retracted and by tightening the screw it is advanced.

An upward and laterally turned extension 38 on the stop plate 28 provides an indicator 39 projecting through slot 23 in the flange 6 of the support and cooperating with a suitable scale 40 preferably of contrasting color, and graduated at 41 to correspond to standard spacings of lines on copy. By reference to this indicator and through the use of the described adjusting means, the actuating mechanism may be set without trial to give desired spacing in indicating the lines of the copy.

The stop mechanism made in accordance with my invention adds greatly to the facility and accuracy of copyholder operation.

65 I claim:

1. In a copy holder the combination with a support, a copy plate and a line indicator mounted thereon, one of which elements is movable relatively to the other, and mechanism for imparting a step-by-step motion to the said movable element embodying an actuating lever, of a stop mechanism for limiting the throw of the actuating lever embodying a carriage movable on the support and adapted for coarse adjustment of position and a stop member in the path of the lever mounted in the carriage and adapted for fine adjustment of position.

2. In a copy holder the combination with a support, a copy plate and a line indicator mounted thereon, one of which elements is movable relatively to the other, and mechanism for imparting a step-by-step motion to the said movable element embodying an actuating lever, of a stop mechanism for limiting the throw of the actuating lever embodying a carriage slidable on the support, means for locking it in different positions of adjustment, a stop member in the path of the lever pivoted to the carriage to move in said path and means for adjusting the stop member relatively to the carriage.

3. In a copy holder the combination with a support, a copy plate and a line indicator mounted thereon, one of which elements is movable relatively to the other, and mechanism for imparting a step-by-step motion to the said movable element embodying an actuating lever, of a stop mechanism for limiting the throw of the actuating lever embodying a carriage slidable on the support, means for locking it in different positions of adjustment, a stop member in the path of the lever pivoted to the carriage to move in said path, a spring tending to retract the stop member, and a regulating screw on the carriage cooperating with the stop member to advance it against the tension of the spring.

4. In a copy holder the combination with a support, a copy plate and a line indicator mounted thereon, one of which elements is movable relatively to the other, and mechanism for imparting a step-by-step motion to the said movable element embodying an actuating lever, of a stop mechanism for limiting the throw of the actuating lever embodying a carriage slidable on the support, means for locking it in different positions of adjustment, a stop member in the path of the lever pivoted to the carriage to move in said path, a scale on the support, an indicator on the stop member cooperating therewith and means for adjusting the latter relatively to the carriage.

5. In a copy holder the combination with a support, a copy plate and a line indicator mounted thereon, one of which elements is movable relatively to the other, and mechanism for imparting a step-by-step motion to

the said movable element embodying an actuating lever, of a stop mechanism for limiting the throw of the actuating lever embodying a carriage slideable on the support and carrying a threaded stud, a nut on the stud for locking the carriage in different positions of adjustment, a stop member in the path of the lever movable on the carriage in said path and an adjusting screw for the stop member extending through the stud and cooperating with the stop member.

6. In a copy holder the combination with a supporting plate having a slotted side flange, a copy plate and a line indicator mounted thereon, one of which elements is movable relatively to the other, and mechanism for imparting a step-by-step motion to the said movable element embodying an actuating lever, of mechanism for limiting the throw of the actuating lever embodying an angular carriage plate slideable in the angle of the supporting plate flange and having a threaded stud projecting through a slot thereof, a nut on the stud for locking the carriage in different positions of adjustment, a stop member in the path of the lever pivoted to the carriage plate and a screw extending through the stud and cooperating with the stop to provide a fine adjustment for regulating its position in the path of the lever.

7. In a copy holder the combination with a support, a copy plate and a line indicator mounted thereon, one of which elements is movable relatively to the other, and mechanism for imparting a step-by-step motion to

the said movable element embodying an actuating lever, of a stop mechanism for limiting the throw of the actuating lever arranged between the support and copy plate 40 and embodying adjusting means, a scale projecting laterally from the side of the support, and an indicator on the stop mechanism projecting laterally to and cooperating with the scale to indicate the position of the 45 stop mechanism.

8. In a copy holder the combination with a supporting plate having a slotted side flange, a copy plate and a line indicator mounted thereon, one of which elements is 50 movable relatively to the other, and mechanism for imparting a step-by-step motion to the said movable element embodying an actuating lever, of mechanism for limiting the throw of the actuating lever embodying an angular carriage plate slideable in the angle of the supporting plate flange and having a threaded stud projecting through a slot thereof, a nut on the stud for locking the carriage in different positions of adjustment, 55 a stop member in the path of the lever pivoted to the carriage plate, a spring for retracting it in the path of the lever, a screw threaded through the stud and cooperating with the stop to advance it in the path of the lever, a scale projecting laterally from the side of the support and an indicator on the stop mechanism projecting laterally through a slot in the supporting plate flange and 60 cooperating with the scale.

JOHN HEBERLING.
